(57) **CLAIM**

The ornamental design for a combined bottle brush cleaning set and holder as shown and described.

DESCRIPTION

FIG. 1 is an exploded front view of a combined bottle brush cleaning set and holder, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof, shown in an alternate configuration; and,

FIG. 8 is a rear perspective view of FIG. 7.

The broken lines depict portions of the design that form no part of the claim.
